UNITED STATES PATENT OFFICE.

WILLIS H. JONES, OF BUFFALO, NEW YORK.

MACHINE FOR CLEANING DRUMS AND THE LIKE.

Application filed July 25, 1923. Serial No. 653,627.

To all whom it may concern:

Be it known that I, WILLIS H. JONES, a citizen of the United States, residing at Buffalo, in the county of Erie and State of New York, have invented a new and useful Improvement in Machines for Cleaning Drums and the like, of which the following is a specification.

This invention relates to a machine which is more particularly designed for cleaning and scouring sheet metal drums, barrels or containers in which paints, varnishes and the like are shipped and stored, although the same may also be used to advantage in cleaning other forms of receptacles.

One of the objects of this invention is to provide a machine for this purpose which permits of thoroughly scouring the interior of the drum or barrel by causing the cleaning medium to act on the surface to be cleaned either lengthwise, or circumferentially, or a combination of these two movements, and also to permit of concentrating the cleaning action on the corners of the drum, or any other part thereof either circumferentially or longitudinally.

Another object of this invention is to so organize the machine that the drum or barrel to be cleaned can be quickly, easily and conveniently secured in the machine and removed therefrom, and also that the same may be adapted for cleaning drums of different lengths. A further object of this invention is to provide simple and efficient means for controlling the motion of the drum to cause the same to either rotate about its own axis, or turn bodily end for end, or combine both of these movements as desired.

In the accompanying drawings:

Figure 1 is a side elevation of a suitable embodiment of my invention. Figure 2 is a vertical longitudinal section of the same taken on line 2—2 of Figure 3. Figure 3 is a top plan view thereof. Figure 4 is a plan view of one of the end supports for the drum or barrel while in the machine. Figure 5 is a fragmentary vertical cross section taken on line 5—5 of Figure 3. Figure 6 is a fragmentary sectional view showing a modification of the means for engaging one end of the drum or barrel to be cleaned.

Similar characters of reference indicate like parts in the several figures of the drawings.

Although this machine is designed to clean and scour the inner sides of various forms

of containers it is particularly useful for cleaning sheet metal drums in which paint or varnish has been shipped or stored so that the same when empty can be used over again. The drum shown in the drawings for illustrating the use of the machine comprises a cylindrical body 10 which is provided with circumferential beads 11, 11, and an opening 12 at one end, and two heads 13, 13 at opposite ends of the body and connected thereto by any suitable means.

The main frame of the machine for cleaning the drum may be variously constructed but in its preferred form the same comprises a base 14, two standards 15, 16, rising from the base at the front and rear ends thereof and two longitudinal bars 17, 18, connecting the standards.

Arranged in front of the front standard is a chuck which is adapted to support the drum while the same is turned either end for end, or circumferentially about the axis of the drum, or a combination of these motions. In its preferred form this chuck comprises a yoke of U-shaped form having a rear cross bar 19, a rigid arm 20 preferably formed integrally with the cross bar and projecting forwardly therefrom and an adjustable arm 21 preferably detachably connected with the other end of the cross bar and projecting forwardly therefrom. This yoke is so mounted that the same is capable of rotation about a horizontal axis for which purpose the central part of its cross bar is preferably mounted on the front end of a horizontal longitudinal shaft 40 which is journaled in a bearing 22 on the front standard and which is preferably hollow for a purpose which will presently appear. The adjustable arm of the yoke is preferably detachably connected with the cross bar thereof by providing the respective end of this bar with an opening 23 which receives the rear part of the arm 21, a V-shaped recess 24 on the rear part of the lower side of this opening which receives a correspondingly shaped lug 25 on the rear end of the lower side of said arm, a V-shaped lug 26 arranged on the front part of the upper side of said opening and engaging with a correspondingly shaped recess 27 on the side of the central part of said arm,

and a fulcrum pin 28 arranged on the cross bar and adapted to engage the underside of the arm 21 between its recess 27 and its lug 25. The engagement of the lugs 25, 26 with the recesses 24, 27 securely holds the detach-

able arm against lengthwise movement on the cross bar of the yoke, but when it is desired to slide this arm backwardly or forwardly on the cross bar when applying a drum to the yoke or removing the same therefrom this can be done by tilting the front end of the detachable arm downwardly on the fulcrum 28 as an axis sufficiently to disengage the lug 25 from the recess 24 and lug 26 from the recess 27 after which the detachable arm is free to move back and forth in the opening 23 so that the front end of this arm is either out or in operative relation to the drum to be clamped on the yoke.

15 The means for mounting the drum on the yoke are so constructed that the same is capable of being turned in a vertical plane end for end and also turned about the axis of the drum. In the construction shown in Figures 1, 2, 3, and 4 this is accomplished by means which comprise a lower rotatable clamping head 29 having preferably the form of a disk and engaging one end of the drum and a clamping head 30 having preferably the form of a crow foot and adapted to engage with the opposite end of the drum. The clamping head 29 is provided on its inner side or face with centering ribs or projections 31 which engage with the respective head of the drum within the rim 32 thereof and the toes 33 of the other clamping head engage in like manner with the other head of the drum within the rim 32 thereof, whereby the drum being cleaned is securely held against lateral displacement on the clamping heads. The lower clamping head is pivotally mounted on the fixed arm 20 of the yoke by means of a spindle 34 arranged on the lower clamping head and projecting outwardly therefrom in line with its axis and journaled in a bearing 35 on the arm 20, and a clamping and pivot screw 36 working in a threaded opening in the detachable arm of the yoke and having a conical end 37 which engages with a correspondingly shaped seat 38 on the central part of the outer side of the clamping head 30. By means of this clamping and pivot screw the drum may be clamped between the heads of the chuck sufficiently firm to hold the same pivotally in place and it also permits of adapting the clamping means to variations in the lengths of the drum within certain limits. The pivot screw may be held in place after adjustment by means of a lock nut 381 mounted thereon and engaging with the outer sides of the arm 21, as shown in Figure 2. In order to adapt the machine for cleaning drums which vary considerably in length this can be accomplished by placing a spacing sleeve 39 of appropriate length on the spindle 34 between the head 29 and the arm 20, as shown in Figures 1 and 2.

65 The means for turning the drum vertical-

ly end for end and also turning it about its own axis are constructed as follows:

The numeral 41 represents a longitudinal driving shaft arranged with its front part in the hollow shaft 40 while its rear end is journaled in a bearing 42 on the rear standard. Arranged in front of one end of the yoke cross bar is an intermediate shaft 421 which is journaled in bearings 81, 82, on the adjacent parts of the yoke so that the axis 75 of this shaft is parallel with the axis of the drum to be cleaned and at right angles to the axis of the longitudinal shafts 40, 41. Motion is transmitted to this driving shaft by a belt passing around a driving pulley 80 44 secured to the driving shaft. The latter and the intermediate shaft are caused to turn together by intermeshing bevel gear wheels 45, 46 secured to the adjacent ends 85 of these shafts. Motion is transmitted from the intermediate shaft to the lower clamping head of the yoke by a driving gear pinion 47 arranged on the outer end of the intermediate shaft and meshing with a gear rim 48 on the edge of the lower clamping 90 head. This driving pinion is preferably elongated so as to permit this clamping head to be moved toward and from the axis of the yoke within certain limits and still without disturbing the driving connection 95 between this head and the intermediate shaft.

Motion at reduced speed is transmitted from a belt driven pulley 49, which is loose on the shaft 41, to the hollow shaft 40 which connects with the yoke, by a counter shaft 50 journaled lengthwise in bearings 51, 52 on the lower parts of the frame standard and having a gear wheel 53 which meshes with a gear pinion 54 on the driving shaft 105 41, and a gear pinion 55 on the counter shaft meshing with a gear wheel 56 on the hollow shaft 40, as best shown in Figure 2. Between the driving pulleys 44, 49, an idle pulley 57 is mounted loosely on the driving 110 shaft.

Means are provided for holding either of the driving shafts 40, 41 against turning, this being satisfactorily accomplished by two brake drums 58, 59 arranged on the pulleys 44, 49, respectively, two brake bands 60, 61 embracing these brake drums, respectively, and each band being connected at one end to the adjacent part of the main frame, two brake shafts 62, 63, journaled 115 transversely in suitable bearings on the lower part of the main frame and each provided with a pull arm 64 which is connected with the free end of one of the brake bands, horizontal shifting rods 65, 66, connected 120 respectively at their rear ends with operating arms 87, 88, on the brake shafts, and upright operating levers 67, 68 pivoted at their lower ends on the front part of the frame base and connected, respectively, with 125 130

the front ends of the shifting rods 65, 66. These operating levers may be held in their operative position by locking pawls or dogs 69, 70 arranged on the sides of these levers 5 and adapted to engage with ratchet segments 71, 72 on the adjacent part of the main frame.

A belt shifter is provided for shifting the driving belt from the central idle pulley 10 to either of the active pulleys or opposite sides of the same, which belt shifter comprises a fork 73 adapted to embrace the driving belt, a longitudinally movable shipper rod 74 carrying the fork and guided in lugs 15 75 on the main frame, and a shifter lever 76 pivoted on the front part of the main frame and connected with the front end of the shipper rod and provided with a locking dog 77 adapted to engage with a locking segment 78 on the frame.

In the operation of this apparatus the attendant first shifts the parts so that the yoke is arranged with its cross bar upright, its fixed arm down and its detachable arm 25 up, in which position a drum can be conveniently mounted in the yoke of the chuck and as easily removed therefrom. After a drum has been mounted in the yoke the latter together with the drum may be rotated 30 in a vertical plane by shifting the driving belt from the loose pulley to the front loose pulley 49 whereby the hollow shaft 40 is turned at slow speed and causes the drum to be turned end for end so that the scouring or cleaning agents, such as liquid solvents, stones, pieces of chain or the like, 35 which are placed in the drum will be caused to slide lengthwise back and forth on the inner side of the drum and loosen and detach any remnants of old paint, varnish or the like. When thus operating the outer shaft 40 the inner shaft 41 may be left free to turn with the outer shaft by releasing the brake band from the rear brake drum, 40 thereby avoiding turning of the drum about its own axis. If however it is desired to also turn the drum about its own axis while being turned end for end and thus produce a longitudinal scouring action successively 45 on all parts of the drum this is possible by tightening the rear brake band on the rear brake drum, whereby the intermediate shaft which is geared with the stationary central shaft 41 is now caused to turn as the yoke 50 rotates and thus producing a rotation of the drum about its own axis through the medium of transmitting gearing between the same.

If it is desired to only turn the drum 60 about its own axis and not turn the same end for end this is possible by applying the brake band to the brake drum of the front pulley so as to hold the yoke against turning and then applying the driving belt to the rear pulley. Such turning of the drum

independently of any end for end turning is particularly desirable when it is desired to scour the corners of the barrel or the heads of the same very vigorously in case the remnants of its former contents adhere tenaciously thereto. When scouring the corners of the drum it is desirable to bring the yoke to a state of rest when the axis of the drum is slightly inclined which will cause the cleaning elements to gather in the lowermost part of the respective corner of the drum and thus subject the latter as it turned to a thorough cleansing action. In like manner the drum may be tilted into such a position that the cleaning elements lodge in one or the other of the heads so that upon turning the drum thereafter about its axis the same will be effectively scoured.

After the drum has been subjected the required length of time to the cleaning operation of the material placed therein, the drum is turned into such position that its opening is lowermost which will permit the contents of the drum to escape and enable the same to be used for packing another 85 quantity of material.

Inasmuch as the construction of the machine is such that the front of the same is unobstructed and all the mechanism for manually controlling the machine are within convenient reach from a point adjacent to the front of the machine it is possible to expeditiously mount and discharge the drums from the machine and to operate the machine conveniently, thus effecting a considerable economy in the cost of doing this work.

In the modified form of my invention shown in Figure 6 a gear wheel 80 is employed which has its hub journaled in the fixed lower arm of the yoke but held against longitudinal movement therein and having its teeth meshing with a gear pinion 85 on the intermediate shaft. Sliding lengthwise in the hub of this gear wheel but compelled to turn therewith is a spindle 86 upon the end of which is mounted a clamping head 83, preferably of crow foot shape which is adapted to engage one head of the drum to be cleaned or scoured and thus cause said 105 drum to be turned during this operation. In order to adapt the clamping head to drums of different length a spacing sleeve 84 of the right length is applied to the spindle 82 between its head 83 and the gear wheel 80. This construction also permits of cleaning drums of varying length without disturbing the mechanism for turning the drum about its axis.

I claim as my invention:

1. A machine of the character described comprising a U-shaped yoke adapted to turn about a horizontal axis and having a transverse bar provided at one end with a fixed arm upon which one end of a drum is adapt-

ed to be mounted while its other end is provided with an opening, a recess on the rear part of the inner side of said opening and a lug on the front part of the outer side of said opening, and a detachable arm upon the front end of which the other end of the drum is adapted to be mounted and the rear end of which is arranged in said opening and provided on the rear part of 10 its inner side with a lug and on the central part of its outer side with a recess which is adapted to engage with the recess and lug of said bar, respectively.

2. A machine of the character described comprising a U-shaped yoke adapted to turn about a horizontal axis and having a transverse bar provided at one end with a fixed arm upon which one end of a drum is adapted to be mounted while its other end is provided with an opening, a recess on the rear part of the inner side of said opening and a lug on the front part of the outer side of said opening, and a detachable arm upon the front end of which the other end of the drum is adapted to be mounted and the rear end of which is arranged in said opening and provided on the rear part of its inner side with a lug and on the central part of its outer side with recesses which are adapted to engage with the recess and lug of said bar, respectively, and a fulcrum pin arranged on said bar and engaging with the inner side of said detachable arm between its recess and lug.

3. A machine of the character described comprising a U-shaped yoke adapted to turn about a horizontal axis and having a transverse bar provided at one end with a fixed arm upon which one end of a drum is adapted to be mounted while its other end is provided with an opening, a recess on the rear part of the inner side of said opening and a lug on the front part of the outer side of said opening, and a detachable arm upon the front end of which the other end of the drum is adapted to be mounted and the rear end of which is arranged in said opening and provided on the rear part of its inner side with a lug and on the central part of its outer side with a recess, said lug and recess on said detachable arm adapted to engage with the recess and lug of said bar, respectively, the co-operating surfaces of said lugs and recesses being V-shaped.

4. A machine of the character described comprising a rotatable yoke upon which a drum to be cleaned is adapted to be mounted, means for turning said drum about an axis at right angles to the axis of said yoke, means for turning the yoke, means for holding said yoke against turning, and means for holding said drum against turning about its axis.

5. A machine of the character described comprising a rotatable yoke upon which a

drum to be cleaned is adapted to be mounted, a hollow outer shaft upon which said yoke is mounted, means for pivotally mounting said drum on said yoke to turn about an axis at right angles to the axis of said yoke, means for turning said drum about its axis comprising an inner shaft arranged within said outer shaft, driving pulleys operatively associated with said shafts, and holding devices associated with said shafts to prevent rotation thereof.

6. A machine of the character described comprising a rotatable yoke upon which a drum to be cleaned is adapted to be mounted, a hollow outer shaft upon which said yoke is mounted, means for pivotally mounting said drum on said yoke to turn about an axis at right angles to the axis of said yoke, means for turning said drum about its axis comprising an inner shaft arranged within said outer shaft, a driving pulley secured to said inner shaft, a driving pulley adapted to turn freely on said inner shaft, and a reducing gearing interposed between said last mentioned pulley and said outer shaft.

7. A machine of the character described comprising a rotatable yoke upon which a drum to be cleaned is adapted to be mounted, a hollow outer shaft upon which said yoke is mounted, means for pivotally mounting said drum on said yoke to turn about an axis at right angles to the axis of said yoke, means for turning said drum about its axis comprising an inner shaft arranged within said outer shaft, a driving pulley secured to said inner shaft, a driving pulley adapted to turn freely on said inner shaft, and a reducing gearing interposed between said last mentioned pulley and said outer shaft, comprising a counter shaft, a gear wheel secured to said counter shaft and meshing with a pinion on said last mentioned pulley, and a pinion arranged on said counter shaft and meshing with a gear wheel on said outer shaft.

8. A machine of the character described comprising a rotatable yoke upon which a drum to be cleaned is adapted to be mounted, a hollow outer shaft upon which said yoke is mounted, means for pivotally mounting said drum on said yoke to turn about an axis at right angles to the axis of said yoke, means for turning said drum about its axis comprising an inner shaft arranged within said outer shaft, a driving pulley secured to said inner shaft, a driving pulley adapted to turn freely on said inner shaft, and a reducing gearing interposed between said last mentioned pulley and said outer shaft, comprising a counter shaft, a gear wheel secured to said counter shaft and meshing with a pinion on said last mentioned pulley, and a pinion arranged on said counter shaft and meshing with a gear wheel on said outer shaft, a brake drum arranged on said outer shaft, a brake drum arranged

on each of said pulleys, and a brake band engaging each of said brake drums.

9. A machine of the character described comprising a rotatable yoke upon which a drum to be cleaned is adapted to be mounted, a hollow outer shaft upon which said yoke is mounted means for pivotally mounting said drum on said yoke to turn about an axis at right angles to the axis of said yoke, means for turning said drum about its axis comprising an inner shaft arranged within said outer shaft, a driving pulley secured to said inner shaft,

a driving pulley adapted to turn freely on said inner shaft, a reducing gearing interposed between said last mentioned pulley and said outer shaft, a loose pulley mounted on said inner shaft between said driving pulleys, a belt shifter for moving the driving belt from the loose pulley to either of said driving pulleys and holding means for preventing said driving pulleys and associated parts from turning.

In testimony whereof I affix my signature.

WILLIS H. JONES.
